CLAIM

The ornamental design for a key ring holder, as shown and described.

DESCRIPTION

FIG. 1 is a top perspective view of a first embodiment of key ring holder according to my design,

FIG. 2 is a bottom perspective view thereof,

FIG. 3 is a left side view thereof, the right side view being a mirror image,

FIG. 4 is a perspective view showing the base holder activated and the ring pin separated therefrom,

FIG. 5 is a left side view thereof showing the base holder activated and the ring pin separated therefrom,

FIG. 6 is a top plan view,

FIG. 7 is a left side view,

FIG. 8 is a top perspective view of a key ring holder showing a second embodiment of my design,

FIG. 9 is a bottom perspective view of FIG. 8,

FIG. 10 is a left side view of FIG. 8, the right side view being a mirror image,

FIG. 11 is a top perspective view of FIG. 8, showing the base holder activated and the ring pin separated therefrom,

FIG. 12 is a left side view of FIG. 8, showing the base holder activated and the ring pin separated therefrom,

FIG. 13 is a top plan view of FIG. 8; and,

FIG. 14 is a left side view of FIG. 8.
